UNITED STATES PATENT OFFICE

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA

APPARATUS FOR CRACKING OIL

Application filed February 11, 1921, Serial No. 444,234. Renewed February 21, 1929.

- This invention relates to improvements in apparatus for cracking oil and refers more particularly to that type of process and apparatus in which the oil is first passed 5 through a relatively closed coil or heating chamber and then delivered in substantially liquid form to an enlarged expansion chamber. Vapors are taken off from such expansion chamber and subject to dephlegmation.
- 10 The particular feature of the present invention lies more especially in the novel means for controlling the temperature of the dephlegmator and at the same time obtaining the highest heat efficiency from the fuel 15 used for initially heating the oil in the cracking zone.
- In the drawing, the single figure is a view, partly in vertical section, and partly in side elevation, of improved apparatus for carrying out our process.
- 20 Referring in detail to the drawing, 1 designates a furnace, provided with the burner 2, stack 3, and combustion chamber 4. In the combustion chamber is mounted the heating 25 coil 5 which may take the form of a continuous coil of 3" pipe formed by interconnected tubes. The inlet side of the coil is connected to inlet line 6 leading to charging pump 7. The outlet side of the coil is connected to the 30 transfer line 8 leading to the elongated expansion chamber 9. This expansion chamber is provided with manhole plate 10, residue drawoff pipe 11 and vapor outlet pipe 12. The last named pipe extends into the 35 lower end of the dephlegmator 13. A spaced cap member 14 is provided above the pipe 12 to prevent the reflux condensate from falling back into the expansion chamber. The dephlegmator consists of the upper and 40 lower drums 15 and 16 connected by the tubes 17, surrounded by the annular heat enclosing shell 18. The drum 16 is provided with the reflux return pipe 19 leading to feed line 6. Its lower side is provided with the branch 45 pipe 20 whereby the reflux condensate may be led elsewhere if desired. The upper chamber 15 is provided with the vapor pipe 21 leading to the condenser coil 22 seated in condenser box 23. The lower end of the coil is 50 connected by pipe 24 with the top of receiver 25. This receiver 25 has pressure gauge 26, liquid level gauge 27, gas outlet pipe 28 and distillate drawoff pipe 29. Various parts of the system are provided with the throttle valves 30, as shown in the drawing, whereby 55 vapor pressures may be maintained on all or part of the system or differential pressures maintained.
- Referring now more particularly to the novel feature of the invention, to the lower 60 end of the shell 18 is connected an air blower 31, which is adapted to deliver regulated quantities of cool air to the dephlegmator so as to definitely and accurately control the temperature of the dephlegmator. As the air 65 passes around the tubes of the dephlegmator, it, of course, serves to cool the oil and itself becomes heated. The heat units thus transferred, instead of being wasted, are saved and utilized by causing them to pass through 70 the insulated hot air pipe 32 connected to the upper end of the shell 18 at one end and at its other end leading back to the burner whereby the hot air may be utilized in connection with the air supply of the burner and 75 thus get a more efficient combustion than would be the case where cool air was used, the pipe being preferably provided with a part 33 for connecting the same with the burner. The construction seems simple but 80 it is to be borne in mind that in the cracking of petroleum oil, one of the major expenses is the fuel required for heating the oil to be cracked. As a matter of fact, in the commercial operation of cracking processes, 85 large amounts of fuel oil are consumed in heating the oil to be treated, which fuel oil might itself be cracked and thus tend to serve to conserve the fuel supply of the country.
- We claim as our invention:
1. In an apparatus for cracking oil, the combination with a still mounted in a furnace, of a dephlegmator connected to the vapor space thereof, and a closed air chamber within the interior of said dephlegmator, means connected to said dephlegmator for forcing cool air thereto and means for removing the air heated by the dephlegmator and delivering it to the furnace of the still. 95
  2. In an apparatus for cracking oil, the 100

combination with a heating coil mounted in a furnace, a reaction zone communicating therewith where substantial vaporization takes place, a dephlegmator communicating with the vapor space of said reaction zone, a closed air chamber within the interior of said dephlegmator, means communicating with said closed chamber in the dephlegmator for forcing cool air thereto, and means for re. 5 moving said air after passage through the closed air chamber which has been heated by the dephlegmator, and means for delivering said heated air to the furnace.
